E. P. BURNHAM

HEAT EXCHANGE APPARATUS

Filed August 10, 1920

Inventor

Elbridge Palmer Burnham

By C. J. Stockman Attorney

UNITED STATES PATENT OFFICE.

ELBRIDGE PALMER BURNHAM, OF NEW YORK, N. Y., ASSIGNOR TO THE ALVEY-FER-GUSON COMPANY, OF OAKLEY, CINCINNATI, OHIO, A CORPORATION OF OHIO.

HEAT-EXCHANGE APPARATUS.

Application filed August 10, 1920. Serial No. 402,519.

This invention relates to a heat exchange apparatus, and more particularly to an apparatus for handling articles which must be given a temperature treatment in the course of manufacture by passing the same through a heated or cooled chamber.

It has always been a problem in such apparatus to prevent the escape of the heated air from heating or drying ovens, or the 10 rush of heated air into cooled chambers when the articles to be treated were introduced or removed from the oven or chamber.

My invention has for its object to overcome this difficulty, and to provide an apparatus which will reduce to a minimum the loss from these causes, and it is equally applicable to the handling of articles which are heated or dried in ovens, as painted or 20 enameled goods, as to the handling of articles to be cooled, as candy and rubber mixtures. The particular adaptation, which I have selected for the purpose of illustrating my invention, is the handling of tubes, such 25 as are used for tooth paste, soaps, etc., just after they have been lithographed, and before the ends are closed off, when they must be slowly dried to prevent cracking or peeling. The present method of handling such 30 articles is to place them upon racks and leave them in a heated room for at heat twelve hours.

My invention consists broadly in the provision of a heated or cooled chamber with 35 a tunnel entrance combined with an article carrier adapted to traverse the tunnel and chamber and provided with means for closing the tunnel while the carrier is passing therethrough. More particularly the invention 40 consists of a heated or cooled chamber with a tunnel entrance and exit combined with article carriers which are provided with walls or end boards of dimensions approximating those of the cross sectional area of 45 the tunnels, and in the provision of means for aiding the passage of the carriers through the tunnels and chamber.

Other objects and advantages of the invention will hereinafter appear in the following detailed description, and the novel features thereof will be particularly pointed out in the appended claims.

In the drawings, Figure 1 is an elevation of an oven with a portion of the entrance 55 tunnel broken away to show the article car-

riers passing through the same; Figure 2 is a cross section through one end of the oven, and Figure 3 is a perspective of one form of carrier which may be used with my invention.

Like parts are indicated by like reference numerals throughout the several figures of the drawing.

The numeral 10 illustrates an oven, which may be of any length required for the heating of articles to be treated. At either end of said oven is an elongated passage forming a tunnel; 11 indicates the entrance tunnel while 12 indicates the exit tunnel. These tunnels are usually of a cross sectional area 60 considerably less than that of the oven and relatively long as compared with their height or width. Preferably they are made long enough to receive a plurality of article carriers, which are introduced into the 65 entrance tunnel from a table 14 and are delivered from the exit tunnel upon a table 15.

It is advantageous to provide means for advancing the carriers and their contents through the tunnels and chamber at a regulated speed and a desirable means for this purpose comprises a conveyer 16 of the endless belt or endless apron type, which passes through the tunnels 11 and 12 and the chamber 10. Said conveyer is driven at any suitable speed demanded by the treatment of the articles handled, and it rests upon the rollers 17, 17, which have been mounted in recesses within the oven for the purpose of permitting the conveyer to travel close 70 to the bottom of the tunnels and heated chamber. The end rollers 19, 19, are mounted upon any suitable support and constitute the means through which the conveyer is driven. The conveyer belt is of a width 75 slightly less than that of the tunnels in order to pass easily therethrough. The oven is provided with any suitable heating means, but as shown the coil 20 has been deemed sufficient for the purposes of illustration.

The article carriers may be of any suitable form to conform to the size and shape of the tunnels and should have means for properly supporting the particular article to be treated and essentially there is provided a tunnel closure member or members travelling 80 with the carrier. The form of carrier selected for illustration is shown in Figure 1 and consists of a base 21 with end boards or 85 walls 22, 22. The base is of a width to neat- 90

ly fit within the tunnels of the oven while the walls of the carrier have a width and height corresponding to that of the tunnels. The base of the carrier is provided with 5 spikes or other retaining devices for supporting the articles to be treated in the oven.

In the form of carrier shown in Figure 3, one of the end boards or walls has been omitted. It is in all other respects similar 10 to that shown in Figure 1.

In the use of the invention, the carriers are fed into the tunnel 11 and as the walls or end boards thereof are approximately of the same cross sectional area as the tunnel, it 15 will be seen that no considerable leakage of heated air can occur. It is advantageous to have more than a single carrier in the tunnel at a time in order to provide a plurality of tunnel closing walls to more effectively prevent the escape of air from the oven. A preliminary treatment of the article will take place within the tunnel, but the main treatment of the articles takes 20 place while the carrier is passing across the body of the oven. The carriers are supported in their travel through the tunnel and the oven upon the conveyer 16. As the articles leave the oven, a gradual change in 25 temperature takes place while passing through the tunnel. This is very advantageous with some articles which have to be cooled slowly. The delivery of the carriers from the oven through the exit tunnel also tends to conserve the heat within the oven 30 by providing walls which will prevent the outrush of the air from the oven.

It will be seen that I have provided an apparatus which will effectively conserve the heat of an article treating chamber and 40 avoid the loss of heat energy heretofore experienced in chambers of this type when the article carrier was introduced into or delivered therefrom. While I have shown and described my invention in connection with 45 an oven, it will be understood that it is just as applicable to any heat exchange chamber, as for instance, in connection with a refrigerating chamber, in which there is a cooling coil and in which the articles are

cooled or chilled. The apparatus may also 50 be used for treating articles in a wet or dry air or gas bath.

Having described my invention, what I claim as new and desire to secure by Letters Patent is:

1. In a heat exchange apparatus, the combination of a treating chamber having an elongated passage forming a tunnel entrance thereto, an article carrier movable into said chamber through said tunnel, and means carried by said carrier for closing said tunnel throughout the travel of the carrier therethrough.

2. In a heat exchange apparatus, the combination of a treating chamber having elongated passages respectively forming an entrance tunnel and an exit tunnel, an article carrier movable into and out of said chamber through said tunnels and carrying means for closing said tunnels throughout 70 the travel of the carrier therethrough, and means for conveying a plurality of carriers through said chamber and tunnels.

3. In a heat exchange apparatus, the combination of a treating chamber having an elongated passage connected thereto, means for carrying articles between said chamber and the outside through said elongated passage, partitions on the carrying means for closing the passage, the passage being 89 longer than the distance between the partitions.

4. In a heat exchange apparatus, the combination of a treating chamber having an entrance tunnel and an exit tunnel, a series of article carriers for passing through said entrance tunnel, through said chamber and through said exit tunnel, said carriers being of less length than the tunnels and provided with partition members of a shape corresponding with the cross section of the tunnels, whereby the tunnels are completely closed while the carriers are moving therethrough, and means for conveying the carriers through said tunnels and chamber.

In testimony whereof I affix my signature.
ELBRIDGE PALMER BURNHAM.
